BOTTLE CLOSURE

Howard W. Meader and Victor V. Pedone,
San Francisco, Calif.

Application April 11, 1955, Serial No. 500,396

6 Claims. (Cl. 215—42)

This invention relates to a new and improved closure for receptacles such as bottles, jars and the like. More particularly, the invention relates to a press-fit type closure cap in which the major component is made of plastic material and which is adapted to be forcibly telescoped over the beaded mouth of a bottle jar or the like in fluid seal relationship therewith.

All permanent press-fit type bottle caps and jar closures on the market today and of which we are aware utilize metal as the major component material from which the closures are made. Conventional cork gasketed crimped-metal bottle caps, and annular rubber or plastic gasketed press-fit metal jar-tops are perhaps the most prevalent example of prior art metal closures of the character above-mentioned.

One apparent reason it has not been considered feasible to manufacture such closures solely or primarily from relatively cheap, commercially available plastic material is that no satisfactory commercially feasible way has been devised to provide and insure an adequately tight and positive fluid seal between the plastic closure and the mouth of the bottle or jar. Thus, in conventional press-fit bottle caps and jar tops of the type above-mentioned, the closure body comprises a metal cover defining a lid portion and depending sides and in each instance the metal sides are pressed or tensioned into forceful and snug embrace around the beaded mouth opening of the bottle or jar to provide the necessary leak-proof press-fit.

It is a principal object of the present invention to provide a positive seal press-fit closure for bottles, jars or the like, or like containers which utilize a relatively cheap, rust-proof, and substantially indestructible plastic material as the major component material of the closure but which also insures attainment of a positive closing seal through utilization of a spring metal contraction band which is partially embedded in the relatively plastic component.

Numerous resultant, subsidiary, and incidental objects and advantages of the present invention will become apparent upon reading the following specification and referring to the accompanying drawings in which similar characters of reference represent corresponding parts in each of the several views.

In the drawings:

Fig. 1 is an enlarged perspective view of a bottle cap embodying the invention shown applied to the mouth of a bottle shown fragmentarily.

Fig. 2 is a transverse sectional view taken on line 2—2 of Fig. 1.

Fig. 3 is a fragmentary sectional view taken on line 3—3 of Fig. 2.

Fig. 4 is a fragmentary sectional view taken on line 4—4 of Fig. 2.

Fig. 5 is a fragmentary sectional view taken on line 5—5 of Fig. 2.

Fig. 6 is a fragmentary sectional view similar to Fig. 2 and showing the unwinding tab partially unwound.

Referring now more specifically to the drawings, a glass beverage bottle of more or less conventional construction and design is indicated fragmentarily and generally at A; and a bottle cap embodying the invention shown applied to the bottle mouth is indicated generally at B. The bottle A may be considered as representative of that type

2

which is extensively utilized to bottle carbonated beverages, beer, and other types of beverages and liquid food products. The neck 11 of the bottle terminates in a beaded mouth portion 12. It is conventional to close bottles of the type illustrated with metal cork gasketed bottle caps that are tightly crimped or press-fitted over the mouth of said bottles.

The bottle cap structure B embodying the present invention is illustrated as comprising an integral plastic body defining a lid portion 13 and annular depending side walls 14. Although the specific composition of plastic material of the cap does not itself constitute a part of the present invention, it is appreciated that the plastic should be selected from a class which is non-deleteriously affected by contact with the beverage or other item bottled, and which also possesses the characteristics of being reasonably resiliently deformable so that the plastic can be forcefully and deformably pressed over the beaded mouth of the bottle in the manner to be explained hereinafter. Polyethylene, for example, comprises one particularly satisfactory type of material for most ordinary bottle capping applications.

An annular recessed groove 16 is formed in the depending side walls 14 of the plastic body. The groove is indicated as being disposed below and adjacent to the lid portion 13 of the plastic cap. The purpose and function of the groove 16 will also be described hereinafter in more detail.

The present bottle cap further incorporates an annular contraction band, indicated generally at 17. This band 17 is shown as comprising a length of light gauge spring metal corrugated throughout its length to define a series of oppositely facing nodes 18a and 18b. In the drawings the band is corrugated to define a series of sine curves. This sinusoidally corrugated length of metal is, in turn, formed into generally circular pattern with one end portion 17a thereof contiguously overlying the opposite end extremity 17b thereof.

Annular contraction band 17 is at least partially embedded within the plastic material defining the depending side walls 14 of the plastic cap body. More specifically, the outer nodes or sine curves 18a of the corrugated circular band are embedded within the plastic material, whereas the inner nodes or sine curves 18b of the band project inwardly from the plastic side walls 14 of the cap. Preferably, ends 17a-17b of the contraction band overlap one another by about one and one-half corrugations and these overlapped corrugated ends embedded within the plastic function to lock the band as a closed ring and prevent the same from separating or splitting open upon forceful press-fit application of the cap over the beaded mouth of a bottle which the cap is adapted to close.

The tip portion of overlapped end 17a of the band extends tangentially outwardly beyond the plane of the plastic cap body a slight distance, and this extended portion in turn is coated with the plastic material to define a manually engageable unwinding tab, such as indicated at 19 in the drawing.

The overall operation and function of the present cap will now be described:

In the manufacture of a cap embodying the invention the interior diameter of the plastic cap body is made slightly smaller than the exterior diameter of the beaded mouth 12 of the bottle which the cap is adapted to close. The transverse distance or diameter of the circular corrugated contraction band (measured from oppositely disposed inner nodes 18b) is also made substantially less than the diameter of the beaded mouth 12 and also perceptibly less than the exterior diameter of that portion of the bottle mouth or neck 12a which the contraction band is adapted to resiliently and contractively em-

brace when the cap is press-fitted into position over the beaded bottle mouth. In this regard, the plastic cap body with contraction band 17 partially embedded therein in the manner above described may be forcefully pressed over the mouth 12 of the bottle by any suitable bottle capping means (not shown). Forceful application of the cap over the enlarged beaded mouth 12 will cause the sine curves or nodes 18a-18b to resiliently deform and flatten and consequently result in enlargement of the band so that it can be forcefully telescoped over the bottle mouth.

As above indicated, the resiliently deformed partially flattened inner nodes 18b of the contraction band are adapted to engage the bottle neck portion 12a in tight spring pressure embrace sufficient to maintain the plastic material in tight fluid-seal relation with the beaded mouth 12 of the bottle. In certain bottling applications it may be considered desirable to line the interior or underside of the lid portion 13 of the cap with a suitable gasketing material, such as cork for example, indicated at 21.

Once a cap of the present type has been applied to close the mouth of the bottle, the same may be readily removed by the ultimate consumer without having to resort to conventional bottle openers or other mechanical instruments. In this connection to remove the cap from the bottle a user need only manually pull the tear-off tab 19 outwardly and unwind the same to cause the plastic material in which the overlapped ends 17a and 17b are embedded to rupture. Rupturing of the plastic embedding the overlapped band ends operates to convert the contraction band into a split-ring structure whereby spring pressure embrace of the band around the bottle neck is released and whereby the metal band may readily enlarge to permit the cap to be slipped over and off of the enlarged beaded mouth opening 12 of the bottle. In order to facilitate tearing of the plastic body as the tab 19 is unwound the aforementioned annular groove 16 is formed around the outer circumference of the plastic cap body. The groove leaves only a very thin strip or bridge of plastic, such as indicated in 16a, joining the lid portion 13 of the cap with the side walls 14. It is around this weakened bridging strip 16a that the plastic material easily ruptures and tears to permit the tab 19 to be easily manually unwound.

Although we have described the invention with specific reference toward providing a cap or closure for bottles, it is believed apparent that jar tops and similar receptacle closures embodying the invention could also be utilized with equal advantage.

Moreover, although the present invention has been described in some detail by way of illustration and example for purpose of clarity of understanding it is understood that certain changes and modifications may be practised within the spirit of the invention as limited only by the scope of the claims appended hereto.

We claim:

1. A press-fit closure adapted to be forcibly telescoped over the mouth of a receptacle such as a bottle, or jar, or the like comprising: a cap formed of plastic material defining a lid portion and annular depending side walls; an annular contraction band at least partially embedded in the plastic sides of said cap; the interior diameter of said cap measured in the plane of said contraction band being slightly less than the outer diameter of the mouth of the receptacle over which said closure is adapted to be forcibly telescoped; said contraction band resiliently expandible to permit said cap to be forcibly telescoped over the mouth of said receptacle; said contraction band exerting a resilient contractible force around the receptacle mouth operable to maintain the plastic sides of the cap snugly embraced around said mouth opening and in fluid seal relationship therewith.

2. The combination of claim 1 and wherein said contraction band comprises a corrugated length of spring metal defining a series of sine curves; said corrugated

length of spring metal arranged in circular pattern defining an annulus; the inwardly extending sine curves of said annulus operable to partially resiliently deform and flatten in spring pressure embrace around the receptacle mouth.

3. The combination of claim 1 and wherein said contraction band is provided with an appendage defining a manually engageable unwinding tab; and wherein said contraction band is embedded in said plastic as a tear strip operable upon manual unwinding force applied to said tab to cause rupturing of the plastic material and cause release of resilient contraction force exerted by said band around the receptacle mouth.

4. A press-fit closure adapted to be forcibly telescoped over the beaded mouth of a receptacle such as a bottle or jar comprising: a cap formed of plastic material defining a lid portion and annular depending side walls; an annular contraction band at least partially embedded in the plastic sides of said cap; said annular contraction band comprising a corrugated strip of relatively resilient spring-metal defining a series of sine curves and formed in substantially circular pattern with at least one sine curve adjacent one end of said strip overlapped with a sine curve formed adjacent the second end of said strip; said overlapped ends embedded in said plastic to maintain said band as a closed ring; the interior diameter of said cap measured in the plane of said contraction band being less than the outside diameter of the beaded mouth of the receptacle over which said closure is adapted to be forcibly telescoped; said contraction band through resilient flattening of its sine curves being resiliently expansible to permit said cap to be forcibly telescoped over the beaded mouth of said receptacle; the contractual energy exerted by the resiliently flattened sine curves operable to maintain the plastic sides of the cap snugly embraced around the beaded mouth opening of the receptacle in substantial fluid seal relationship therewith.

5. A press-fit closure adapted to be forcibly telescoped over the beaded mouth of a receptacle such as a bottle or jar, comprising: a cap formed of plastic material defining a lid portion and annular depending side walls; an annular contraction band at least partially embedded in the plastic sides of said cap; said annular contraction band comprising a strip of relatively resilient spring metal formed throughout its length with a series of sine curves

45 and formed in substantially circular pattern with at least one sine curve adjacent one end of said strip overlapped with a sine curve formed adjacent the second end of said strip; said overlapped ends embedded in said plastic to maintain said band as a closed ring; the interior diameter of said cap measured in the plane of said contraction band being less than the outside diameter of the beaded mouth of the receptacle over which said closure is adapted to be forcibly telescoped; said contraction band through resilient flattening of its sine curves being resiliently ex-

50 pansible to permit said cap to be forcibly telescoped over the beaded mouth of said receptacle; the contractual energy exerted by the resiliently flattened sine curves operable to maintain the plastic sides of the cap snugly embraced around the beaded mouth opening of the receptacle in substantial fluid seal relationship therewith; one overlapped end of said contraction band defining an outwardly extending manually engageable tab; said contraction band embedded in said plastic as a tear strip operable upon manual unwinding force applied to said tab to

55 rupture the plastic embedding the overlapped ends of said band and allow said band to operate as a split-ring in its removal from the beaded receptacle mouth.

6. The combination of claim 5 and wherein the plastic material defining the sides of the cap is formed with an annular groove disposed above the contraction band and below the lid portion defining a plane of weakness in the plastic to facilitate rupturing of the plastic and unwinding of the said tab.
